UNITED STATES PATENT OFFICE.

AARON M. SPRINGER, OF PORTLAND, OREGON, ASSIGNOR, BY MESNE ASSIGNMENTS, TO OREGON WOODENWARE MANUFACTURING COMPANY, A CORPORATION OF OREGON.

IRONING-TABLE.

1,132,528.

Specification of Letters Patent. Patented Mar. 16, 1915.

Application filed October 13, 1913. Serial No. 794,778.

To all whom it may concern:

Be it known that I, AARON M. SPRINGER, a citizen of the United States, residing in the city of Portland, county of Multnomah, 5 and State of Oregon, have invented certain new and useful Improvements in Ironing-Tables, of which the following is a specification.

This invention relates to ironing tables of 10 the character shown and described in Letters Patent No. 868,500, granted to me October 15, 1907, and in Letters Patent No. 1,012,468, granted to me December 19, 1911.

The primary object of this invention is to 15 make certain improvements in the ironing boards shown and described in my Letters Patent just referred to, whereby the board can be made cheaper and with less iron therein, without surrendering any of its 20 qualities. In all of these boards the most important feature is a construction wherein all weight which may be placed upon the board, whether in the middle of the board, or at the free end thereof, is transmitted 25 longitudinally of the leg and brace members and wherein there is absolutely no strain laterally upon any leg or brace member, and at the same time the free end of the board projects for nearly half the entire length of 30 the board free of any leg or brace members which would interfere with the placing of a garment telescopically thereover. Because of this construction the board is absolutely rigid and without any springing or yielding 35 movements when in use, and a man's weight can be supported upon the outermost end of the board without springing or tipping the board. This is due to the fact that the weight upon the board is all transmitted 40 through the brace and leg members, from one to the other, longitudinally thereof, and in no instance is there any lateral strain upon the legs or upon any brace member. In this invention, I have preserved all of 45 these features and at the same time have greatly reduced the amount of iron and wire used in the board, and have made use of pieces of wood which would otherwise be thrown away as waste. The result is to 50 materially lessen the cost of manufacture, without in any way detracting from the efficiency of the board.

I have shown my improved board in the accompanying sheets of drawings, which I 55 will now describe.

In the drawings,—Figure 1 is a perspective view of the board set up in readiness for use; Fig. 2 is a bottom plan view of the board with the parts all folded together; and Fig. 3 is a fragmentary sectional view 60 showing how the inclined brace member engages with the under side of the board when in use.

Referring again to the drawings, 1 designates the top or board, 2—2 vertical legs, 3 an inclined leg member of double construction, 4 an inclined brace, and 5 a brace wire. The vertical legs 2—2 are braced together by means of top and bottom pieces 2^a—2^b, and two inclined brace members 2^c. Two vertical members 2^e—2^e are secured to the inside of the top and bottom members 2^a and 2^b so as to fold closely between the members of the inclined leg 3. The vertical legs 2—2 and the inclined leg 3 are pivotally connected to the under side of the board by means of a rod 6, through blocks 7—7, secured to the under side of the board. The lower end of the inclined brace member 4 fits between the vertical members 2^e—2^e and 80 is pivotally connected thereto by means of a short rod 8. The brace member 5 is a wire turned back upon itself to form a long loop, as at 5^a, which loop rests in a long slot 4^a in the lower end of the brace 4 and around the short rod 8. When the board is folded said loop moves over said short rod 8 and the adjacent part of the wire lies within the slot 4^a. The opposite end of said wire brace is 85 also formed into a short loop, as at 5^b, shown in dotted lines, between the lower ends of the inclined leg 3 and around a short through pin which connects said leg members together, as indicated. The upper end of the inclined brace member 4 fits against a block 9 upon the under side of the board 1, and is held in place when the board is open for use by means of a small hook 10. This construction makes it possible to fold the board 95 flatly, the folded board being no thicker than the thickness of the board itself and the breadth of the leg members 2—2 and the outside brace members 2^a—2^b, less than four inches in all. In this construction, I use a 100 double inclined leg member spaced apart at its upper end and brought together at its lower end as indicated, with a cross piece, as 3^a. This cross piece, however does not engage the inclined brace 4, and has no other function than to hold the two members of 105 110

the inclined leg 3 in rigid relationship with each other. I also use a single wire brace 5 and provide it with the long loop, whereby in folding the board the wire loop can pass 5 backwardly over the rod 8, and thus I eliminate the necessity of having a jointed pair of wire brace rods to facilitate the folding operation. The vertical leg structure 2—2 also makes it possible to use a very short 10 iron rod to hold the lower end of the inclined brace 4, and to transmit the pull to the wire brace 5.

Assuming now that a very heavy weight is placed upon the outer end of the board, the 15 strain is transmitted lengthwise through the inclined brace member 4 to the short rod 8, and thence becomes a direct pull upon the wire brace 5, and thence becomes a pull lengthwise of the inclined leg 3, the upper 20 end of which is secured to the opposite end of the board. The spread of the legs 2—2 gives a good base to prevent side tipping, and the inclined leg 4 is back far enough at its upper end so as to give much free open 25 space directly under the free end of the board, making it possible to put a skirt or shirt over the end of the board without any obstructions whatever, and upon a very rigid board.

30 I am aware that slight changes can be made from this particular construction without departing from the spirit of my invention, and I do not limit the invention to this specific form, except as I may be limited 35 by the hereto appended claims.

I claim:

1. An ironing table of the character described, comprising in combination, a top or board, a substantially vertical leg structure 40 pivoted thereto adjacent one end thereof, an inclined leg pivotally secured to said top adjacent said vertical leg structure, an inclined brace pivotally secured to said vertical leg structure and passing through said 45 inclined leg and adapted to be detachably secured to the under side of the board, and a brace rod secured to the lower end of said inclined leg and having a loop and pin con-

nexion at its opposite end with said vertical leg structure, whereby all strain from weight 50 upon said board is transmitted lengthwise of the leg and brace members, substantially as described.

2. An ironing table of the character described, comprising in combination, a top or 55 board, a substantially vertical leg structure pivoted thereto adjacent one end thereof, an inclined leg of double construction having its members pivotally secured to said top at a space apart and adjacent said vertical leg 60 structure, and its members brought together at their lower ends, an inclined brace pivotally secured to said vertical leg structure at one end and passing between the members of said inclined leg and adapted to be detachably secured to the underside of said board, said brace member having a slot 65 formed in its lower end, and a wire brace member pivotally secured at one end to the lower end of said inclined leg and provided 70 at its opposite end with a slot-like loop which is connected through the slot in said inclined brace member to said vertical leg structure, substantially as and for the purpose described.

3. A folding ironing table comprising in combination a top, a vertical leg structure pivotally secured to said top adjacent one end thereof, an inclined leg structure pivotally secured to said top at the same end, an 80 inclined brace structure pivotally connected to the vertical leg structure and detachably connected to said top, and a brace member connected at one end to the lower end of said inclined leg structure and at its other end 85 by a loop and pin connection to said vertical leg structure, whereby the latter can move forwardly, in folding, through said loop.

Signed at Portland, Oregon, this 4th day 90 of October, 1913.

AARON M. SPRINGER.

In presence of—

F. A. BULLINGTON,
G. A. NICHOLS.
